UNITED STATES PATENT OFFICE.

ELISHA R. BETZER, OF MEDINA, OHIO.

CORING INSTRUMENT.

1,190,711.

Specification of Letters Patent. Patented July 11, 1916.

Application filed July 23, 1913. Serial No. 780,788.

To all whom it may concern:

Be it known that I, ELISHA R. BETZER, a citizen of the United States, residing at Medina, in the county of Medina and State 5 of Ohio, have invented certain new and useful Improvements in Coring Instruments, of which the following is a specification.

This invention relates to cutlery and more 10 particularly to a hand operated instrument or tool for removing the eyes from pineapples.

The object of this invention is the provision of a hand operated tool for removing the eyes from pineapples, which has the outer or cutting ends or jaws of the same shaped so as to engage and remove the entire eye from the pineapple and leave no part of the same therein and also a tool 20 of this nature which has the inner ends of its jaw open so that the eyes will fall out of the tool immediately after they have been removed from the pineapple.

With the foregoing and other objects in view this invention consists in such novel 25 features of construction, combination and arrangement of parts as will be hereinafter more fully described, illustrated in the accompanying drawings and claimed.

In describing the invention in detail reference will be had to the accompanying 30 drawings wherein like characters designate the like or corresponding parts throughout the several views and in which,

Figure 1 is a side elevation of the improved coring instrument. Fig. 2 is a top plan view of the same. Fig. 3 is an end view of the improved corer and Fig. 4 is 35 a sectional view through the jaws of the corer showing the manner in which they are formed.

Referring more particularly to the drawings the numeral 1 designates the handle portion of the improved eye removing instrument which has its outer end 2 flared 45 so as to form a convenient grip for the person using the instrument. The inner end of the handle portion 1, which handle is constructed of sheet metal is bent and 50 curved upon itself forming a hollow spoon shaped jaw 3. The handle 1 of the coring instrument has a slot 4 formed intermediate its outer flared end 2 and the spoon shaped portion 3 which is formed upon the inner 55 end and the slot 4 has seated therein the end 5 of the shank portion 6 of a second

spoon shaped jaw 7. The end 5 of the shank 6 is held in place and the jaws 3 and 7 are pivotally connected by means of a pin or rivet 8 which is inserted through the sides of the handle 1 and through the end 5 of the shank 6. The spring 10 is coiled about the pin 8 as at 11 and has its end 12 seated in an opening in the shank 6 of the jaw 7 and its end 13 extending through an opening 14 formed in the jaw 3. The spring 10 is coiled between the pin 8 in such a manner that it will hold the jaws 3 and 7 apart at all times. The jaws 3 and 7 are slightly enlarged as at 15 and 60 shaped so as to efficiently engage the eye of a pineapple and encompass the entire eye and have their pointed ends 16 sharpened and curved inwardly as is clearly shown in Figs. 1 and 3 of the drawings 65 so as to cut the eye from the pineapples when the points of the jaws 3 and 7 have been forced into the pineapple.

For removing the eyes from a pineapple the jaws 3 and 7 are forced into the pineapple (not shown) so that an eye (not shown) of the same is between the two jaws. When the jaws have been forced into the pineapple the desired distance they are 70 pressed together by manual power and the 75 pressing together of the jaws will cut the eye from the pineapple and as the rear ends of the spoon shaped jaws 3 and 7 are open as is clearly shown in Fig. 4 of the drawings 80 the eye will immediately fall from 85 between the jaws and no extra motion will be necessary for removing the eyes from the jaw.

In practical fields certain minor features of construction, combination and arrangement of parts may necessitate alterations 90 to which the patentee is entitled provided such alterations are comprehended within the scope of what is claimed.

What is claimed is:

1. In an eye remover for fruits or vegetables, a pair of semi-ovoid pivoted jaws provided with bulged sides, the free extremities of said jaws being broadened adjacent the points thereof, each of said jaws having an aperture therethrough, and a means trained intermediate its ends around the pivot of the jaws, the ends of which means pass through said apertures and engage with the outer face of the jaws to normally hold the jaws in spaced relation.
2. A fruit or vegetable eye remover com-

prising a pair of pivotally connected jaws which are constructed to provide a plurality of complemental guideways longitudinal thereof when the jaws are in a closed position.

3. A fruit or vegetable eye remover comprising a pair of semi-ovoid pivotally connected jaws, each of which is provided with a central partition dividing the jaws into compartments, thus forming elliptical passageways when the jaws are closed, and

means secured through apertures in the jaws and trained about the pivotal connection of the jaws to hold them normally spaced apart.

In testimony whereof I affix my signature in presence of two witnesses.

ELISHA R. BETZER.
